Fig. 1.

Ediphalt Nott.

Case "g"

Letters Patent.

The Schedule referred to in these Letters Patent and making part of the same, containing a description in the words of the said Mr. Ediphalt Nott, himself of his improvement in the material, form, and construction of stove pipe to be employed when anthracite coal is the fuel in use.

Case "No. g."

Specification of improvements made in the material, form and construction of stove pipe to be employed, when anthracite coal is the fuel in use. Whereas great inconvenience has arisen in the use of anthracite coal, from the escape of gas, when the heat has been impeded, from, and the smoke passed off in a sheet is often reverberated in the usual manner by stones, as well as from the destruction of the flue itself, on account of the great weight of the smoke arising from said coal, and a corresponding necessitation of the acid contained therein. Therefore an improvement has been introduced, and the same having been tested and perfected by repeated experiments, is deemed worthy of being carried into general use, which improvement consists, in making use of rough, cast iron, hollow, parallel pipes, for so much of the flue as it is desirable to employ for giving off to the room the requisite heat. The same to be adjusted vertically, in place of smooth sheet iron, hollow, cylindric, either with or without reverberation, which may be effected by combining either by screws, or bolts, or any other expedient, two opposite rough and wide plates, with two opposite, rough and narrow ones, in such manner that the same shall contain little interval of space and present much external surface; that is shall resemble each a hollow parallel pipe. And by connecting such flue to the flue to be directed by placing one section thereof upon another, and adjusting them together.

together in such manner that the upper one shall either set over into the under one; the former being preferable - or by placing an open cover over, and confining the same to the lower section in covering any arched, around its contained opening for the purpose of receiving and leading the upper section when set thereon; and that whether the ends of the calibre thereof, shall be fitted to the outer side or the inner side of said arched, the two in either case to be secured or bolted together; - It is to be understood that said parallelopipeds may present any external form though some regular architectural form is preferred. The calibre of said flue, for a common stove, should be about two inches deep; and the wider the better, provided the same do not exceed in width the stove itself; and the construction will be more perfect, if a groove be sunk on the inner face, and at the outer edge of the wider plates, for receiving the edges of the two narrower ones, when adjusted in place. For further information, reference may be had to the drawings hereto appended, by which it may be seen, how the ends of flue are held by a groove in the front and back; and how two sections may be combined by intermediate castings. Summary. The improvement herein contemplated, consists in securing a draft; in increasing the conducting and radiating power of the flue, so that it will give off to the room the requisite heat, without being reverberated; and in preventing the destruction of the flue itself, by making use of rough, cast-iron pipe, in the form of hollow parallelopipeds, in place of smooth, sheet-iron pipe in the form of cylinders, for so much of the flue, as it may be desirable to employ for giving off the requisite heat to the room.

I therefore claim as my invention & improvement, the securing of the draft; - the increasing of the conducting and radiating power of the flue, and the preventing of the speedy destruction of the flue itself, by making use of rough, cast-iron pipe, combined as aforesaid, in the form of hollow parallelopipeds, in place of smooth, sheet-iron pipe in the form of hollow cylinders, for so much thereof, as it may be desirable to employ for giving off the requisite heat to the room, together with
